APPARATUS FOR CASTING SLEEVE-LIKE BODIES

Thomas A. Moermann, Pleasant Ridge, Mich., assignor to The Forging & Casting Corporation, a corporation of Michigan

Application September 10, 1934, Serial No. 743,376

2 Claims. (Cl. 22—65)

This invention relates to improved centrifugal molding apparatus and method for centrifugally molding metal articles.

One of the main objects of the invention is to provide an improved method and apparatus of this character by which the outer surface of the centrifugally cast article may be formed to an irregular or undulated contour.

A further object of the invention is to provide an improved method and apparatus of this kind by which passages may be formed in the wall of a cylindrical hollow article during centrifugal casting thereof.

A still further object of the invention is to provide for the formation, in the wall structure of a hollow centrifugally cast article, of passages which would present difficulties in machining such, for instance, as passages which extend at diverse and selected inclinations to the axis with respect to which the molten metal is revolved during the centrifugal casting operation.

Other objects of the invention are to provide, in a centrifugal casting mold, a destructible lining element having its inner surface complementary

to the outer surface contour desired on a centrifugally cast article; to provide an irregular or undulated contour on the inner surface of a centrifugal casting mold lining for forming complementary undulations and irregularities in the

outer surface of a centrifugally cast article; to provide a self-sustaining lining of this character which is adapted to be formed externally of the mold and stored for use in subsequent casting operations; to provide a lining of this kind which

is conveniently insertable in the mold and adapted to be placed therein immediately after completion of a casting operation and without waiting for the mold to cool; to provide a destructible centrifugal casting mold lining element which

is conveniently removable from the mold after an article cast therein has solidified; and to provide a removable partial end closure for the mold which has a substantially central charging opening therein that is adapted to admit molten metal

to the interior of the mold during rotation of the latter at a comparatively high speed.

A further object of the invention is to provide for the formation of passages through, or impression in, the wall of a centrifugally cast article without the aid of a mold lining.

Still further objects of the invention are to provide individual passage-forming cores in a mold of this character and means for holding the cores therein in predetermined position; to provide passage-forming cores of this kind which

may be positioned at divers inclinations with respect to each other and with respect to the axis of rotation of the mold; to provide an improved method of forming composite cylinder liners by a centrifugal casting operation which may be conducted in either of the foregoing lined or unlined molds; to provide a method of this kind by which the particles of the different metals forming the composite cylinder liner are thoroughly commingled at the junction of the different portions thereof; and to provide for the introduction of a non-oxidizing or reducing gas into the interior of the mold during operation thereof so as to prevent excessive oxidation of the metal or metals.

An additional object of the invention is to provide improved centrifugal casting method and apparatus which are particularly adapted for the formation of sleeves such as cylinders.

A still further object of the invention is to provide an improved integral, centrifugally cast, hollow metal article having passages in its wall structure and having an irregular or undulated exterior.

The above being among the objects of the present invention, the same consists in certain novel features of construction, combinations of parts and steps of operations that will hereinafter be described with reference to the accompanying drawing and then claimed, having the above and other objects in view.

In the accompanying drawing which illustrates suitable embodiments of the present invention, and in which like numerals refer to like parts throughout the several different views.

Fig. 1 is a side elevational view of a centrifugal casting apparatus showing the improved mold thereof in longitudinal vertical section.

Fig. 2 is a side elevational view of a cylinder liner of the type used in Diesel engine cylinders, illustrating a specific article which may be advantageously cast in the improved apparatus and in accordance with my improved centrifugal casting method.

Fig. 3 is a horizontal sectional view of the cylinder liner taken on the line 3—3 of Fig. 2.

Fig. 4 is a fragmentary view, similar to Fig. 1, but showing a modified form of the invention.

Fig. 5 is an enlarged fragmentary sectional view taken through the wall of a preferred type of engine cylinder liner which may be advantageously formed by use of the apparatus disclosed in either Fig. 1 or 4.

In the form of the invention illustrated in Fig. 1, the improved centrifugal casting appara-

tus includes a base or support 10 upon which a driving member 11 is mounted, the driving member being shown, for the purpose of illustration, as an electric motor although any suitable driving means may be used. The driving member 11 is provided with a shaft 12 having a fixture 13 on its outer extremity upon which a centrifugal casting mold, generally designated by the numeral 14, is detachably mounted by bolts 15. The mold 14 includes a metal cylindrical casing 16 having a closed extremity 17 into which the bolts 15 are threaded, and the opposite extremity 18 of the cylinder 16 is open.

Mounted in the interior of the cylinder 16 is a destructible lining sleeve 19 which preferably comprises core material which may be of any suitable type such as is employed for baked cores in usual foundry practice. The lining sleeve 19 is self-sustaining in shape and is preferably formed externally of the mold 14 so that sleeves of this character may be produced in any desired numbers and stored for use in future casting operations. This sleeve is insertable into the interior of the cylinder through the open end 18 thereof and its outer periphery conforms with and closely fits the inner periphery of the cylinder. In the form shown, the bore of the cylinder tapers outwardly from the closed end 17 thereof, but this tapered relation of the cylinder wall, while usually desirable, is not essential and the latter may be straight if desired.

The inner surface of the sleeve 19 is formed to a contour complementary to that desired on the exterior of the final product. In the illustration shown in Figs. 1, 2 and 3, the article is a cylinder liner sleeve, generally designated by the numeral 20, of the type used in Diesel engines and it has a radially extending external flange 21 on one extremity and spaced radially extending external flanges 22 intermediate its extremities. Located between the flanges 22 of the liner sleeve 20 is a series of circumferentially spaced exhaust ports or passages 23. The exhaust ports 23 extend in diverse inclinations to each other and with respect to the axis of the cylinder liner sleeve and it will be understood that such ports would ordinarily present difficulties where necessary to machine them out of a solid sleeve.

The internal side of the mold lining sleeve 19 is provided with spaced grooves 24 and 25 which are complementary to the flanges 21 and 22, respectively, and inwardly extending radial flanges 26 and 27 are provided on the opposite extremities of the mold lining sleeve 19 for defining the extremities of the article being centrifugally cast. Integrally formed on the mold lining sleeve 19 are inwardly extending cores 28 which extend into the interior of the mold and which conform in shape and location with the shapes and locations, respectively, of the ports 23 desired in the finished product.

Mounted in the open extremity of the cylinder 16 is a disk-shaped closure 29 having a central charging opening 30 therein. The internal side of the closure 29 abuts against the outer side of the flange 26 of the mold lining sleeve 19 and holds the latter against unintended displacement from the mold and also retains the inner extremity of the mold lining sleeve in contact with the end wall 17 of the cylinder 16. This closure is releasably held against displacement from the open end of the cylinder 16 by any suitable means, that shown by way of illustration comprising wedges 31 which are fitted in slots formed

in the wall of the cylinder 16, as illustrated in Fig. 1.

The shaft 12 of the driving member 11, fixture 13 and the end wall 17 of the cylinder 16 are provided with communicating passages 32 through which a reducing, or non-oxidizing gas may, if desired, be conveniently supplied to the interior of the mold to prevent excessive oxidation of the molten metal during solidification thereof. The left end of the passage 32 in the driving member shaft 12 is connected by a tube 33 with a suitable source of either non-oxidizing or reducing gas (not shown).

In operation of my improved centrifugal casting apparatus the lining sleeve 19 and closure 29 are assembled in the cylinder 16 in the relation illustrated in Fig. 1, and the cylinder is then rotated by the motor 11 while the charge of moldable material, such as ferrous metal, non-ferrous metal, alloys, or any suitable metallic or non-metallic moldable material, is introduced into the interior of the mold through the charging opening 30. On the other hand, if desired, the charge may be introduced into the mold while the latter is at rest and in this case the mold is promptly rotated after the charging operation. The mold is rotated at a speed sufficiently high to centrifugally evenly distribute the metal around the interior of the mold lining sleeve 19, thereby causing the metal to flow into the grooves 24 and 25 and around the cores, which are preferably of slightly greater length than the thickness of the wall structure of the article. The mold is thus rotated until the metal solidifies and then the wedges 31 are knocked out and the closure 29 is removed so as to permit the cast article to be removed from the cylinder 16 by axial movement with respect thereto. In the particular construction shown the mold lining sleeve may be removed with the cast article and then broken away from it. On the other hand, the mold lining sleeve 19 may stick in the mold, in which case during removal of the finished article the cores 28 and the flange 26 will be sheared off and in some instances the entire lining sleeve broken down, thereby permitting free and easy removal of the article. The cylinder 16 may then be completely cleaned and a new lining sleeve may be inserted immediately after removal of the article and while the mold is still hot.

In the form of the invention illustrated in Fig. 4, the main parts of the centrifugal casting apparatus are substantially identical to those shown in Fig. 1 and corresponding parts of the structures are designated by the same numerals. The cylinder of the mold, generally designated in Fig. 4 by the numeral 16', is provided with a closed end wall 17' and an open opposite extremity 18'. Formed on the open end portion of the cylinder 16' is an offset cylindrical portion 34 which is coaxial with the main body portion of the cylinder. The closure 29 in the open end of the cylinder 16' is normally located in spaced relation to the inner extremity to the offset portion 34 so as to provide a groove 35 which is complementary in shape to a flange 36 desired to be provided on the extremity of the cast article 31. The cast article illustrated is a cylinder sleeve liner for a Diesel engine cylinder.

The wall of the cylinder 16' is provided intermediate its ends with a thickened circumferential portion 38, in registration with which internal recesses 39 are formed for receiving individual cores 40 which are so constructed and arranged as to provide a series of circumferentially spaced

exhaust ports or passages 41 in the finished casting. Also, in using this form of apparatus, before the casting operation the interior of the mold is preferably washed, sprayed or painted with a thin coat 42 of suitable refractory material of the nature sometimes used in connection with casting in permanent molds of conventional construction. In addition, this may be followed by a thin coating of lampblack also in accordance with conventional practice in permanent molds. The coating 42 may last for several casting operations but the lampblack is renewed for each casting operation. It may be noted that a knock out hole 43 may be provided for each recess 39 15 so as to permit the corresponding core 40 to be displaced easily after each casting operation.

The centrifugal casting apparatus illustrated in Fig. 4 is employed in identically the same manner in making a cast article as the apparatus previously described, that is, after the interior surfaces of the mold have been suitably provided with a coating 42, the cores 40 have been inserted in place and the dam 29 secured in position, the mold is set in rotation and sufficient molten metal 25 is introduced through the opening 30 to provide the desired article, or, as previously explained, the molten metal may be introduced through the opening while the mold is at rest and then the mold immediately set in rotation to cause 30 proper distribution of the molten metal around the interior walls of the mold. After the metal has solidified and becomes sufficiently cooled the dam 29 may be removed and the cast article pulled out of the mold shearing the cores 40 during 35 their removal operation. On the other hand the cores 40 may be knocked out by inserting a suitable tool through the various openings 43 prior to removal of the cast article.

Both forms of the apparatus disclosed in the drawing may be advantageously employed for the production of cylinder liners of a composite nature such, for instance, as those having an outer layer of metal having desired characteristics of toughness, rigidity or the like, and an inner wall portion of metal having suitable characteristics to resist the wear and abrasion of the piston which will reciprocate therein or the chemical reaction of the gases and/or liquid with which it will come into contact during operation in an engine. A section through a wall of such composite cylinder liner is illustrated in Fig. 5 in which it will be noted that the liner includes a relatively thick outer portion 45 and a relatively thinner inner portion 46, differentiated from the portion 45 by stippling, although, as will be apparent to those skilled in the art, the relative thicknesses of the two portions may vary as desired. As a matter of illustration it may be assumed that the portion 45 is formed from cast 50 grey iron and the portion 46 formed from a type of metal which may, for instance, readily lend itself to a nitriding treatment.

In forming a cylinder liner of the composite type illustrated in Fig. 5 by the apparatus shown, 55 the same methods as hereinbefore described are followed for forming the outer portion 45, and

sufficient metal is introduced into the rotating or rotated mold to provide the required thickness of the portion 46. In this case it is particularly important that a reducing or non-oxidizing gas is introduced into the mold through the opening 32 to prevent oxidization of the exposed surface of the liner being cast. The mold is rotated and as soon as the metal forming the portion 45 has solidified sufficiently to retain its shape, additional molten metal of a composition 10 required to form the portion 46 is introduced into the mold where, because of the relatively greater heat of this second charge of metal and the still relatively high temperature of the first charge of metal and because the exposed surface 15 of the first charge has been kept from oxidizing, the contacting surface layers of the two charges will intimately commingle throughout their entire areas and be fused together in such a manner that there will be no distinct line of separation 20 between the two portions 45 and 46 when the liner is completed. This insures that in the finished article there will be perfect heat conducting bond between the two portions of the liner and that there will be no danger of one of the portions separating from the other during service. The bond is also such that, regardless of subsequent heat treating or other operation upon the liner, the two portions will retain their intimate bond with one another. 30

With either of the foregoing centrifugal casting apparatuses and methods high speed production of centrifugally cast cylindrical articles having passages in their wall structures located intermediate their extremities may be economically 35 conducted. By employment of the mold lining sleeve 19, illustrated in Fig. 1, it is possible to centrifugally cast the exterior of an article to substantially any desired irregular contour.

Although but several specific embodiments of the invention have been herein described, it will be apparent to those skilled in the art that various changes may be made therein without departing from the spirit and substance of the broad invention, the scope of which is commensurate 45 with the appended claims.

I claim:

1. In centrifugal casting apparatus including a hollow casing having an open extremity, a lining sleeve comprising core material insertable in 50 said casing and including an integral core extending inwardly of said sleeve for forming an opening in the wall structure of an article cast in said casing.

2. In centrifugal casting apparatus, a mold including a hollow cylindrical casing having a core recess in its interior and having an opening registering with said recess and extending through the wall of said casing, and a destructible core replaceably mounted in said recess and extending 55 toward the central portion of said casing, the portion of said core disposed in said recess being removable therefrom by insertion of a suitable instrument into said opening from the exterior of said casing. 60

THOMAS A. MOORMANN. 65
